JOHN S. McWHIRTER, OF NEW YORK, N. Y.

CAR-CONTROL MECHANISM.

1,332,403.

Specification of Letters Patent.

Patented Mar. 2, 1920.

Application filed February 18, 1919. Serial No. 277,873.

To all whom it may concern:

Be it known that I, JOHN S. McWHIRTER, a citizen of the United States, residing at New York, county of New York, State of 5 New York, have made a certain new and useful Invention in Car-Control Mechanism, of which the following is a specification.

My invention relates to systems of control and to car-control mechanism or apparatus, 10 and especially to the improved control of "one-man" or "quick-service" cars.

One object of the invention is to provide a car-control mechanism which is simple in structure, efficient in operation and economic of manufacture. 15

A further object of the invention is to provide a car-control mechanism for electrically driven vehicles, which may be readily installed on the electrically driven vehicles now in use. 20

Another object of the invention is to provide a simple and efficient "one-man" control mechanism for street cars, or other electrically driven vehicles. 25

A further object of the invention is to provide a mechanism of the character described which may be readily applied to the electrically operated street cars now in use to convert them into "one-man" cars. 30

More specifically stated, it is an object of my invention to provide a combined propelling and braking control system of the above-indicated class which shall be adapted for ready and reliable control by an operator's foot, the system being preferably adapted to effect a pre-selected degree of automatic acceleration of the propelling motor or motors. 35

Other objects of the present invention will 40 become evident from the following detailed description, taken in conjunction with the accompanying drawings, wherein

Figure 1 is a view, in front elevation, of the front of an electrically driven vehicle, such as a street car, looking from within and showing control mechanism employed in accordance with my invention. 45

Fig. 2 is a top plan view of the brake control mechanism. 50

Fig. 3 is a sectional view taken on the line III—III, Fig. 2, and looking in the direction of the arrows. 55

Fig. 4 is a view, in front elevation, with parts broken away, and Fig. 5 is a view, in

side elevation, of the current-control mechanism employed in accordance with my invention. 55

Fig. 6 is a top plan view of a foot-control mechanism contemplated as one form of my invention. 60

Fig. 7 is a view, similar to Fig. 2, showing a slightly modified construction. 65

Fig. 8 is a diagrammatic view of a system of automatic control organized in accordance with the present invention. 65

The same part is designated by the same reference character wherever it occurs throughout the several views.

It is among the special purposes of my present invention to provide what is known 70 as a "one-man" or "quick-service" car; that is, a passenger-carrying car, wherein a single operator is provided, the one operator acting to control the car movements, to open and close the car doors for the admission and exit 75 of passengers, to collect the fares, to issue transfers and to otherwise do the necessary duties incident to serving as both a conductor and a motorman on the present type of structure. 80

I further contemplate means for rendering a car of this nature absolutely safe for the passengers contained therein, whereby, in case of accident or negligence of the motorman or conductor, the car will come to a 85 stop, with its brakes applied. In other words, in the normal condition of the car, its brakes are applied and in its abnormal condition, current is being supplied to its motor. I wish it to be understood, however, 90 that, while I have shown, and will hereinafter describe, my invention as applied to a "one-man" street car, the invention is not to be limited or restricted in this respect, as it might be applied to any elevated or subway 95 car or any electrically driven vehicle, or to any railway system. Therefore, where I hereinafter refer to "car," I desire to include thereby any such electrically driven vehicle. In the street cars now in use, it is customary 100 to mount the motor-controller or master-controller, the car-brake-control mechanism and, if desired, the car-door-operating mechanism at the motorman's station at the front of the car. In accordance with my invention, I so connect the motor controller and the brake mechanism, that, when the controller is in its "off" position, the brakes are

105

set. I also provide means for releasing the brakes and thereby simultaneously applying current to the motor.

Referring to the drawing, I show at 1, the front of a car on which the motor controller—in this instance, a controller 2—is located. The brake mechanism is illustrated as of the pneumatic type, the control thereof being effected through the respective conduits 3, with the brake-valve or control mechanism, indicated at 4, controlled by means of the removable handle 5.

The brake-control valve 4 may be of any suitable or standard type and, for the purposes of illustration, I show a standard construction (see Figs. 2 and 3) comprising a stem 6 surrounded by, and incased in, a stationary collar or sleeve 7 that is provided with a slot 8 to permit the handle 5 to be placed thereover, with the extension or lug 9 adapted to move freely within the stationary sleeve 7, as will be readily understood. The stem 6 of the valve is squared, as shown, and the handle 5 has a square opening that fits over the stem 6, which may thus be turned. It will be seen that the handle 5 can be placed on the stem 6 only when the stem is in a predetermined position—preferably its "lap" or neutral position—relative to the slot 8 of the stationary sleeve 7, and that, after the handle 5 has been positioned on the stem 6, the handle projection 9, upon actuation of the valve in the one or the other direction, rotates within the stationary sleeve 7, thus preventing the removal of the handle 5.

Loosely mounted around the stationary sleeve 7 to rotate relative thereto, is a collar 10 provided with two upwardly extending lugs 11 that are adapted to engage the shank of the handle 5, whereby the stem 6 of the valve is rotated. Pivotal secured, at one end, to the collar 10 is a rod 12, the other end of which is pivotally attached to one arm of a bell-crank lever 13, which is suitably supported by the frame of the car 1. The lower arm 14 of the bell-crank lever is pivotally secured to the top of a vertically-extending rod 15, the bottom of which is pivotally attached to one end of a horizontally-located lever 16. The lever 16 is suitably supported, for pivotal movement intermediate its ends, by a bracket or standard, indicated at 17 and secured to the floor of the car 1. The lever 16 is provided with pins 18 extending on opposite sides thereof to afford a detachable engagement for another lever 19, which, in the form shown, is preferably a pedal.

Suitably affixed to the rod 15 is an arm 20 that is adapted, upon upward movement of the rod 15, to engage a lever 21, which is pivotally secured, as shown at 22, to engage a vertically slidable pin 23 carrying thereon a contacting bridge 24 for establishing circuit connection between a pair of contact

members or terminals 25 and 26 that are located within a casing 27. Thus, it will be seen that, when the pedal 19 is depressed, the rod 12 is moved toward the right and, at the same time, circuit connection between contact terminals 25 and 26 is established. 70

The contact members 25 and 26 are connected in series relation with the motor controller or master controller so that, until and 75 unless the circuit connection is established between the contact terminals 25 and 26, no current can be supplied to the motor. It is my purpose to maintain the contact members 25 and 26 normally open-circuited and, for 80 this purpose, any means may be employed to retain the parts thus far described in the position shown in the drawings: for example, a spring 30, secured at one end to the rod 15 and at the other end to the car body 85 1, may be employed. Also, in this position of the parts (the normal position), I propose to have the valve 4, controlling the brake, in its operative or "brake on" position, so that, in the form shown, with the 90 parts in the position indicated, the brakes are set with the full force of fluid-pressure supply, and current to the motor is shut off by reason of the open circuit between the contact terminals 25 and 26. 95

If pressure is applied to the pedal 19 to raise the rod 15, the circuit connection is established between the contact members 25 and 26, and, at the same time, the action of the bell-crank lever 13, the rod 12 and the 100 rotatable collar 10 engaging the handle 5, causes the handle to turn, thus effecting the release of the brakes to permit the car to move forward. If, for any reason, the pressure is removed from the pedal 19, the 105 spring 30 will retract the lever 15 and the extending arm 20 to the normal position, thus allowing the slidable pin 23 to drop, by gravity, to shut off the current to the motor; and the rod 12, rotating the valve stem 6 as 110 above explained, automatically supplies fluid pressure to the brake mechanism, thus insuring the application of the brakes.

It is the present custom in the street-car art to have the controller, located at the 115 operator's station, of the master-controller type, and connected to govern the motor-controller proper, which, in turn, directly controls the car-propelling motors. The motor-controller is customarily of the automatic-acceleration type, whereby, if the controller handle 32 of the master-controller 2 is turned to its "full on" position and the supplying circuit is closed, the motor-controller will start the car slowly without 120 shock and will automatically "pick up" or increase the voltage that is impressed upon the car-propelling motor in proportion to the increasing speed of the car.

Such a system is illustrated in Fig. 8 and 130

- comprises suitable supply-circuit conductors, respectively marked "Trolley" and "Ground"; a plurality of electric motors respectively having commutator-type armatures A¹ and A² and series field windings F¹ and F²; an accelerating resistor R; a controller 50 having a main or motor-controlling drum or section 51, an auxiliary-circuit or interlocking drum or section 52 and an operating mechanism 53; a current-relay or limit switch L that is energized in accordance with the motor current to govern the movement of the controller 50, in a manner to be set forth; and a battery B or other suitable source of energy for the illustrated auxiliary control system, together with the master controller 2, the brake-control valve 4, the pedal 19 and the interconnecting mechanical parts, as previously described.
- 20 The controller 50 is adapted to occupy a normal "off" position and a plurality of operative positions *a* to *f*, inclusive. A suitable contact segment 60 is located upon the main section 51 of the controller for varying the active circuit value of the accelerating resistor R, while other segments 61 and 62 are adapted to group the illustrated motors in either series or parallel relation, as subsequently described in detail.
- 25 The auxiliary-circuit or interlocking section 52 of the controller 50 comprises a contact segment 63 that is connected in circuit with the master controller and with the pedal-controlled switch member 24 for effecting automatic acceleration of the illustrated motors to any desired stage, such as full-series or full-parallel relation, as herein-after more completely set forth.
- 30 The operating mechanism 53 is of a familiar electrically-controlled, pneumatically-actuated type comprising a pinion 64 which is suitably secured to one end of the operating shaft 65 for the controller 50 to mesh with a horizontally-movable rack member 66, the opposite ends of which constitute pistons 67 and 68 traveling within a suitable operating cylinder 69. A valve 70, having an actuating coil "on," is normally open to the atmosphere and is associated with one end 35 of the operating cylinder 69, while a valve 71, having an actuating coil "off," is normally open to admit fluid pressure from any suitable source (not shown) through a pipe or passage 72 and communicates with the other end of the cylinder. Under normal conditions, the operating mechanism 53 occupies the illustrated extreme left-hand position by reason of the biasing effect of the high-pressure air or other medium that 40 is admitted, through the valve 71, to the right-hand end of the operating cylinder 69.
- 35 The mechanical operation of the mechanism 53, without regard to the electrical connections effected thereby, may be set forth as follows. Upon concurrent energization of the two actuating coils "on" and "off," fluid pressure is admitted through a pipe or passage 73 and the valve 70 to one end of the operating cylinder, and fluid pressure is exhausted from the other end of the cylinder through valve 71 to the atmosphere. Consequently, the initial unbalanced-pressure conditions in the mechanism are reversed to effect a movement of the pistons 67 and 68 toward the right and, therefore, of the controller 50 toward the left through its successive operative positions *a* to *f*, inclusive.
- 45 To arrest such movement at any time, it is merely necessary to deenergize the "off" magnet, whereupon balanced high-fluid-pressure conditions obtain in the two ends of the operating cylinder to effect a positive and reliable stoppage of the mechanism. To return the device to the illustrated normal position, both actuating coils are concurrently deenergized, whereby the fluid-pressure conditions revert to the original unbalanced state and the desired backward movement is effected.
- 50 Assuming that, after the car has been brought to a stop, the motorman selects some master-controller position; then, to start, he merely depresses the pedal 19 to cause the bridging contact member 24 to connect contact terminals 25 and 26. In this case, not only are the brakes released, in accordance with the previously-described procedure, but automatic acceleration to any desired stage, corresponding, for example, to any one of the illustrated positions "Start," "Series" and "Parallel" of the master controller, may be obtained, preferably by throwing the master controller into the desired position as soon as the car 55 has stopped, as already mentioned.
- 55 Assuming that the position pre-selected under the conditions noted is the "start" position and, further, assuming that the foot-pedal 19 is depressed by the motorman, an auxiliary circuit is first established from the positive terminal of the battery B, through conductor 75, contact terminals 25 and 26, which are bridged by the movable contact member 24 of the auxiliary switch, conductor 76, control fingers 77 and 78, which are bridged by contact segment 79 of the master controller, conductor 80, actuating coil or magnet "on" and conductor 81 to the negative terminal of the battery.
- 60 A further circuit is established from the contact segment 79 of the master controller in its "start" position, through control finger 82, conductor 83, control fingers 84 and 85, which are bridged by the contact segment 63 of the interlocking section or drum 52 in its "off" position, whence circuit is continued through conductor 86, contact disk 87 of the current relay L in its lower (low-current) position, conductor 88, 65

the actuating coil "off" and conductors 89 and 81, to the negative battery terminal. Since both actuating coils for the operating mechanism 53 are thus concurrently energized, a forward movement of the controller 50, as far as the first operative position *a*, is effected. The controller movement is arrested in position *a* by reason of the disengagement of the contact segment 10 63 of the interlocking drum from control finger 84, whereby the circuit of the "off" magnet is interrupted and the controller is instantaneously brought to rest, in accordance with the previously-described operating principles.

In position *a* of the controller 50, the main or motor circuit is established from the trolley, through conductor 90, control fingers 91 and 92, which are bridged by the contact segment 20 60 of the controller 50, the entire accelerating resistor R, conductor 93, armature A¹, field winding F¹, conductor 94, control fingers 95 and 96, which are bridged by contact segment 61, conductor 25 97, armature A², field winding F², the actuating coil 98 of the current relay L, and conductor 99, to the negative supply-circuit conductor ground.

The motors are thus started into operation, with a desirably low voltage impressed upon their armatures by reason of the series-circuit relation of the accelerating resistor R.

Assuming that the position of the master controller that is pre-selected by the motorman during the above-mentioned car stop is the "series" position, the control finger 82 does not engage the contact segment 79 of the master controller, this segment now 35 40 making contact with control finger 101, whence circuit is continued through conductor 102, control finger 103, and thence, through the contact segment 63 of the interlocking drum, to the "off" coil.

Consequently, movement of the controller 50 from the initial "off" position, as far as position *c*, is obtained, which position corresponds to full-series relation of the main motors. Controller movement is arrested in 45 50 position *c* by reason of the disengagement of the contact segment 63 from the control finger 103, whereby the "off" coil is de-energized.

It will be understood that the movement 55 of the controller to position *c* is governed by the current relay or limit switch L in a familiar manner; namely, such movement is temporarily arrested when the main-motor current rises to a value sufficient to lift the 60 current relay and interrupt the previously-traced circuit of the "off" coil, while the controller movement is continued whenever the limit switch drops to its low-current position to energize the auxiliary circuit in question.

65 As the controller 50 approaches position *b*,

control fingers 92 and 104 are connected to bridge or short-circuit one section of the accelerating resistor R and thus effect an increase in the motor speed. Similarly, in position *c* of the controller, fingers 104 and 105 70 are bridged to short-circuit the remaining section of the accelerating resistor. Position *c* of the controller 50 thus corresponds to full series relation of the motors, as stated above.

If conditions are suitable for permitting complete automatic acceleration of the motors, the motorman may pre-select the master-controller position marked "Parallel" during the car stop. In this case, control fingers 82 and 101 remain de-energized, while a new circuit is established from the contact segment 79 of the master controller, through control finger 106, conductor 107, and control finger 108, which engages the 85 contact segment 63 of the interlocking drum 52, until the final position *f* thereof is reached.

Consequently, the "off" coil is intermittently energized in accordance with the 90 movements of the current relay L to effect full automatic acceleration of the main motors to parallel relation by producing step-by-step movement of the controller 50 from the "off" position to the final position *f*.

As the controller 50 passes from full-series position *c* to position *d*, shunting transition of the motors to parallel relation is effected. In position *d*, the main circuit is established from the trolley through conductor 90, contact segment 60 of the controller 50, the entire accelerating resistor R and control finger 110, where the circuit divides, one branch including conductor 93, armature A¹, field winding F¹, conductor 94, control fingers 111 and 112, which are bridged by the contact segment 62 of the controller 50, and thence to the negatively connected conductor 99, while the other branch traverses the contact segment 61, control finger 110 96, conductor 97 and thence through the other motor in accordance with the circuit traced during the description of series acceleration.

Positions *e* and *f* of the controller 50 correspond to positions *b* and *c*, in that the sections of the accelerating resistor R are successively short-circuited. Thus, the final position *f* of the controller 50 effects full parallel relation of the car-propelling 115 120 motors.

From the foregoing description, it will be noted that the motorman may pre-select the degree of motor acceleration by placing or leaving his master controller in the corresponding position after the car has been stopped. Then, by merely depressing the pedal 19, the car brakes are released and the auxiliary switch is closed, whereby the car is smoothly accelerated to the desired 130

stage without further attention or manipulation upon the part of the operator.

In other words, when the present type of motor-control mechanism is employed, it will be seen that the motorman may turn his control handle 32, located at his position on the front of the car, to its "full on" position and, merely with one foot, control the entire operation of the car; that is, by pushing the pedal 19 downwardly, the brakes are released and current is supplied to the motor-controller, whereby the car will start from standstill and gradually pick up speed until it has reached its maximum speed. Upon diminishing the pressure on the pedal 19, current to the motor is cut off and the brakes will be gradually applied until the car has come to rest, or until pressure on the pedal 19 is completely removed, in which case the valve 4 occupies its full "brake on" position, which may, if desired, be the emergency position for the brakes. Thus, it will be seen that if, through accident to the motorman or through his negligence, when the car is in motion, his pressure on the pedal 19 is removed, current to the motor is automatically shut off and the brakes are applied.

I have shown the valve handle 5 and the pedal 19 removable, so that the motorman's complete equipment, consisting of two small and light pieces, may be transferred from one end of the car to the other, if necessary. If desired, the master-controller handle 32 may likewise be removable. It will be noted, however, that, to remove the handle 5 of the brake-controller, it is necessary to place the valve in its "lapped" or neutral position in any suitable manner, for example, by means of depressing the pedal 19, thus rotating the valve 5 to its lap or neutral position, to enable the lug 9 thereof to pass through the slot 8. Consequently, after the removal of the handle 5, when the pressure is removed from the pedal 19, even though collar 10 is placed in its normal position, the valve 4 remains in its "lap" or neutral position, since the rotation of the collar 10, after the removal of the handle 5, does not cause the rotation of the valve stem 6.

It is well known in the art, for example, as shown in my Patent No. 1,169,552, issued January 25, 1916, to provide door switches in circuit with the controller, so that, though the controller is in its "on" position, and a door is open, no current is supplied to the car-propelling motor. In a "one-man" car contemplated in my invention, it is necessary to have the door-control mechanism, if doors are employed in connection therewith, within easy reach of the single operator of the car, and for this reason, I show shaft 35 for controlling the operation of the door 65 upon the rotation thereof by means of a re-

movable handle 36, such as shown and described in my copending application, Serial Number 65,481, filed December 7, 1915, whereby, with the door switch referred to in connection with my above-identified patent, the operator, if desired, may leave his controller handle 32 in "on" position and merely open the door, thereby opening the circuit of the motor. With the door open and the pedal 19 depressed to release the brakes and close the circuit between the contact terminals 25 and 26 to initiate the forward movement of the vehicle, it is merely necessary to close the door and the car will start forward slowly in the manner above described.

From the foregoing description, it will be seen that I have provided a car-control mechanism which may be operated wholly by the foot of an operator positioned at the front end of the vehicle or at the station provided for him, for the purpose of controlling the vehicle operation, leaving his hands free to receive fares, issue transfers, control the movements of the doors, if desired, and, in general, to do with his hands whatever may be required. It is obvious, however, that, if desired, rather than employ a foot pedal, the handle 5 may be operated in place thereof to accomplish the same results.

Referring to the modification shown in Fig. 7, the spring 30 may be dispensed with to normally maintain the parts in the position shown, that is, with the contact terminals 25 and 26 open-circuited and the brakes applied when there is no pressure on the pedal 19. In this arrangement, I show a cylinder 40, open at one end and closed at the other, with the closed end placed in communication, by means of a pipe 41, with a constant source of fluid-pressure supply. A piston 42 is located in the cylinder, the piston rod 43 of which extends through the open end of the cylinder 40 and is pivotally connected, by means of a rod 44, to the rod 12 and the collar 10. Thus, it will be seen that, when pressure is applied to the pedal 19, forcing the rod 12 to the right, the piston 42 acts against the constant pressure from the pneumatic reservoir, and, when pressure on the pedal 19 is diminished, the pneumatic pressure from the reservoir causes the piston 42 to travel toward the left, thus restoring the parts to their normal positions, with the circuit of the motor controller open and the brakes applied.

This application is a continuation in part of my copending application, Serial No. 221,635, filed March 11, 1918.

I do not wish to be restricted to the specific structural details, circuit connections or arrangement of parts herein set forth, as various modifications thereof may be made without departing from the spirit and scope

of my invention. I desire, therefore, that only such limitations shall be imposed as are indicated in the appended claims.

I claim as my invention:

5 1. The combination with a car and a car controller and brake control device, of a handle for manually governing said brake control device and foot-operated means for normally retaining the circuit of said controller open and actuating said handle to keep the brake control device applied.

10 2. The combination with a car and a car controller and brake control device, of a handle for manually governing said brake control device, means for normally retaining the circuit of said controller open and actuating said handle to keep the brake control device applied, and foot-governed means, for closing said circuit and actuating said handle for simultaneously releasing said brake control device.

15 3. The combination with a car, of a motor controller, a brake control device for said car, a handle for manually governing said brake control device, a circuit for supplying current to said controller, and means responsive to the release of foot-pressure for simultaneously opening said circuit and actuating said handle for effecting a brake-applying action of said brake control device.

20 4. The combination with a car, of a motor controller, a brake control device for said car, a handle for manually governing said brake control device, a circuit for supplying current to said controller, and foot-actuated means for simultaneously closing said circuit and actuating said handle for effecting a releasing action of said brake control device.

25 5. The combination with a car, a car controller and a brake control device, of a circuit for controlling said controller, a switch for controlling said circuit, and foot-operated means for simultaneously and adjustably controlling said switch and said brake control device.

30 6. The combination with a car, a car controller and a normally applied brake control device, of a handle for manually governing said brake control device, a circuit for controlling said controller, a normally open switch for controlling said circuit, and foot-governed means for simultaneously closing said switch and actuating said handle for effecting a releasing action of said brake control device.

35 7. The combination with a car, a car controller, and a brake control device, of a handle for manually governing said brake control device, a circuit for controlling said controller, a switch for controlling said circuit, means normally tending to actuate said handle to retain said brake control device applied and to retain said switch open, and

40 65 foot-controlled means for simultaneously

closing said circuit and actuating said handle for releasing said brake control device.

8. The combination with a car, a car controller, and a brake control device, of a circuit for controlling said controller, a switch for controlling said circuit, means for adjustably controlling said brake control device, and means actuated thereby for controlling said switch.

70 9. The combination with a car, a car controller, and a brake control device, of a circuit for controlling said controller, a switch for controlling said circuit, foot-operated means for adjustably controlling said brake control device, and means controlled thereby for controlling said switch.

75 10. The combination with a car, a car controller, and a brake control device, of a circuit for controlling said controller, a switch for controlling said circuit, manually operated means for controlling said brake control device, means controlled thereby for controlling said switch, and a removable pedal for controlling said manually operated means.

80 90 11. The combination with a car, a car controller and a brake control device, of a handle for manually governing said brake, a circuit for controlling said controller, a switch for controlling said circuit, foot-operated means for actuating said handle for controlling said brake control device, means actuated thereby for controlling said switch, and means normally tending to actuate said handle to retain said brake control device in its "on" position and to retain said switch opened.

95 100 12. The combination with a car, a car controller, and a brake control device, of a circuit for controlling said controller, a switch for controlling said circuit, manually operated means for controlling said brake control device, means controlled thereby for controlling said switch, a removable pedal for controlling said manually operated means, and means normally tending to retain said brake control device in its "on" position and said switch opened.

105 110 115 120 13. The combination with a car, a car controller and a brake control device, of a circuit for controlling said controller, a switch for controlling said circuit, manually operated means for controlling said brake control device, a lever for actuating said brake-controlling means, means carried by said lever for controlling said switch, and means normally retaining said lever in retracted position, with said brake control device applied and said switch open.

125 14. The combination with a car, a car controller and a brake control device, of a circuit for controlling said controller, a switch for controlling said circuit, manually operated means for controlling said brake control device, a foot-operated lever for actuat-

130

- ing said brake-controlling means, means carried by said lever for controlling said switch, means normally retaining said lever in retracted position, with said brake control device applied and said switch open, and a removable pedal for actuating said lever.
15. The combination with an electric controller and a brake valve located side-by-side, of an operating handle for said brake valve, means for engaging said handle in operative position, and means comprising a link-and-lever mechanism having one end positioned to positively actuate said engaging means at all times for effecting a substantially simultaneous operation of said handle and government of the controller circuits.
16. The combination with an electric controller and a brake valve, of an operating handle for said brake valve, means for engaging said handle in operative position, and means comprising a link-and-lever mechanism having one end positioned to actuate said engaging means, a movable pedal attached to the other end of said mechanism, and a switching device located near said controller and adapted to be operated by said mechanism.
17. The combination with an electric controller and a brake control device, of a handle for governing said brake control device, a normally open switching device located near said controller for governing the circuits thereof, and a remotely-controlled link-and-lever mechanism for effecting a substantially simultaneous operation of said handle to release said brake control device and close said switching device.
18. The combination with an electric controller and a brake valve, of an operating handle for said brake valve, a collar loosely inclosing said valve and having means for engaging said handle, a rod located near said controller and biased to a certain position, mechanical means for joining the upper end of said rod to said collar, and a pedal movably secured to the lower end of the rod for effecting a substantially simultaneous movement of said handle and government of the controller circuits.
19. The combination with an electric controller and a brake valve located side-by-side, of an operating handle for said brake valve, a collar loosely inclosing said valve and having means for engaging said handle, a rod located near said controller and biased to a certain position, mechanical means for joining the upper end of said rod to said collar, a pedal movably secured to the lower end of the rod, a switch located near said rod for governing the controller circuits, and means actuated by said rod for controlling said switch.
20. In a control system, the combination with a dynamo-electric machine, of means for effecting automatic operation thereof under predetermined conditions, a normally applied brake control device, and means for substantially simultaneously releasing said brake control device and making the automatic means effective.
21. In a control system, the combination with a dynamo-electric machine, of means for effecting automatic operation thereof under predetermined conditions, a normally applied brake control device, and means for substantially simultaneously releasing said brake control device and making the automatic means effective and for rendering said automatic means ineffective and applying the brake control device at will.
22. In a control system, the combination with an electric motor, of a controller having a position corresponding to automatic acceleration of said motor, a normally applied brake control device, and means independent of the controller for substantially simultaneously releasing said brake control device and effecting said automatic acceleration when the controller occupies said position.
23. In a control system, the combination with a dynamo-electric machine, of a switching device for governing the operation thereof, means for effecting automatic operation of said machine when said switching device is closed, a normally applied brake control device, and means for substantially simultaneously releasing said brake control device and closing said switching device.
24. In a control system, the combination with a dynamo-electric machine, of a switching device for governing the operation thereof, means for effecting automatic operation of said machine when said switching device is closed, a normally applied brake control device, and means for substantially simultaneously releasing said brake control device and closing said switching device and for opening said switching device and gradually applying said brake control device at will.
25. In a control system, the combination with an electric motor, of a controller having a position corresponding to automatic acceleration of said motor, a switch for completing the controller circuits, a normally applied brake control device, and foot-operated means for substantially simultaneously releasing said brake control device and closing said switch to effect said automatic acceleration when the controller occupies said position.
26. In a control system, the combination with an electric motor, of a controller having a position corresponding to automatic acceleration of said motor, a switch for completing the controller circuits, a normally applied brake control device, and

foot-operated means for substantially simultaneously releasing said brake control device and closing said switch to effect said automatic acceleration when the controller 5 occupies said position and for opening said switch and gradually applying said brake control device at will.

27. In a control system, the combination with a dynamo-electric machine, of means 10 for effecting a plurality of different automatic operations thereof, a normally applied brake control device, and means for substantially simultaneously releasing said brake control device and making the automatic means effective to produce a pre-selected operation.

28. In a control system, the combination with an electric motor, of a controller having a plurality of positions corresponding 20 to different stages of automatic acceleration of the motor, a normally applied brake control device and means for substantially simultaneously releasing said brake control device and initiating said automatic acceleration to a stage determined by the pre-selection of a controller position.

29. In a control system, the combination with a plurality of electric motors, of a controller having a plurality of positions respectively corresponding to series and to 30 parallel relation and automatic acceleration of the motors, a normally applied brake control device, and means for substantially simultaneously releasing said brake control device and initiating said automatic acceleration with the motors either in series relation or first in series and then in parallel relation in accordance with the pre-selected position of said controller.

40 30. A control system for electrically-driven vehicles comprising means for manually controlling the speed of the propelling motor, a pedal biased to a normal position and having a plurality of other operative 45 positions, a device actuated by the pedal whereby the said controlling means is rendered effective or ineffective, and a valve also actuated by the pedal for controlling the degree of effectiveness of fluid-actuated 50 brakes for the vehicle.

31. A control system for electrically-driven vehicles comprising means for manually controlling the speed of the propelling

motor, a pedal biased to a normal position and having a plurality of other operative 55 positions, a device actuated by the pedal whereby the said controlling means is rendered effective or ineffective, and a valve also actuated by the pedal for controlling the degree of effectiveness of fluid-actuated 60 brakes for the vehicle without opening or closing the said device.

32. A control system for electrically-driven vehicles comprising means for manually controlling the speed of the vehicle-propelling motor, a pedal biased to a normal position and having a plurality of other operating positions, a switch actuated by the pedal for rendering the said controlling means effective or ineffective and arranged 70 to render the controlling means ineffective when the pedal occupies its normal position, and a valve also actuated by the pedal for controlling the degree of effectiveness of fluid-actuated brakes for the vehicle without opening or closing the said switch and arranged to set the brakes when the pedal occupies its normal position.

33. A control system for electrically-driven vehicles comprising means for manually controlling the speed of the vehicle-propelling motor, a switch for rendering the said means effective or ineffective, a valve for causing the fluid-actuated brakes to have varying degrees of effectiveness, and a pedal 85 for actuating both the said switch and the said valve and biased to maintain the switch open and the valve in brake-setting position.

34. A control system for electrically-driven vehicles comprising means for manually controlling the speed of the vehicle-propelling motor, a pedal biased to a normal position and having a plurality of other operating positions, a switch actuated by the pedal for rendering the said controlling 90 means effective or ineffective, and a valve also actuated by the pedal for controlling the degree of effectiveness of fluid-actuated brakes for the vehicle, the said pedal, upon being moved from its normal position, first 100 causing gradual release of the brakes and then closure of the said switch.

In testimony whereof I have hereunto set my hand on this 10th day of February A. D., 1919.

JOHN S. McWHIRTER.
